UNITED STATES PATENT OFFICE.

FLOYD GARWICK, OF CHICAGO, ILLINOIS.

VACUUM FEED MECHANISM.

1,310,393.

Specification of Letters Patent. Patented July 15, 1919.

Application filed February 1, 1919. Serial No. 274,544.

To all whom it may concern:

Be it known that I, FLOYD GARWICK, a citizen of the United States, residing at Chicago, in the county of Cook and State 5 of Illinois, have invented certain new and useful Improvements in Vacuum Feed Mechanism, of which the following is a description, reference being had to the accompanying drawings, forming a part of this specification, in which corresponding numerals of 10 reference in the different figures indicate like parts.

The object of my invention is to provide a simple, cheap and effective vacuum feed 15 mechanism for internal combustion engines, which shall be so constructed as to make a single valve to simultaneously open one and close the other of two passages leading from a vacuum chamber,—one to the intake manifold of the engine and the other to the atmosphere, to enable liquid fuel to be drawn from a main supply tank to the vacuum tank, and, in turn, to be delivered therefrom to an auxiliary container in operative communication with the engine carbureter. To these ends, my invention consists in the combination of elements herein- 25 after more particularly described and definitely pointed out in the claims.

30 In the drawings,

Figure 1, is a vertical sectional view of combined vacuum and auxiliary tanks one within the other, showing in connection therewith the feed controlling mechanism 35 embodying the features of my invention.

Fig. 2, is a diagrammatic view in elevation showing a portion of an engine, a carbureter, and vacuum and supply tanks respectively, and indicating the relation which 40 they would hold to each other.

Fig. 3, is a section taken upon the line 3—3 Fig. 1, viewed from beneath.

Fig. 4, is a section taken upon the line 4—4, Fig. 1, viewed as indicated by the arrow there shown, and

Fig. 5, is an enlarged view of the duplex valve.

Referring to the drawings, 1, indicates an auxiliary tank in which is inclosed a 50 vacuum-tank 2, both having a common top 3 which is detachably secured in place by means of screws 4 and so constructed as to form an air-tight joint. Formed upon the top is a nipple 5, which is connected by means of a pipe 6; Fig. 2, with a main supply or storage tank 7, upon a lower level,

from which liquid fuel may be supplied thereto. The vacuum tank 2 is provided with an outlet tube 8, Fig. 1, leading to the auxiliary tank 1, and having a check-valve 60 9, at its lower end of well known construction, adapted to be closed when a partial vacuum is produced in the vacuum chamber and to open when the pressure therein is equalized, to permit a discharge of liquid 65 fuel from the vacuum tank into the auxiliary chamber. The latter is provided with a discharge opening 10, connected by means of a tube 11, Figs. 1 and 2, with the carbureter 12 of the engine 13. Said carbureter 70 is, in turn, connected in any well known way, with the intake manifold 14, of the engine.

The top plate 3, is provided with an opening therewith which is closed by means of 75 a plate 15, tightly fitted and detachably held in place by means of screws 16; said plate being also shown in Figs. 3 and 4. Extending through said plate or cast integrally therewith, so as to project above and below 80 it, is a member, generally designated by 17, the upper portion of which is bored out and internally threaded to receive a tube 18, Fig. 2, leading to the intake manifold 14. The part 17 is provided with a reduced vertical bore 19, which is intersected by a horizontal bore 20, terminating at its outer end in a valve seat adapted to receive the conical end 23, of a cone-shaped valve generally 85 designated by 24. The bores 19 and 20 described constitute a vacuum passage in communication with the vacuum-tank 2, and the pipe 18 leading to said intake manifold. A depending vent or equalizing member 25, 90 is formed upon or attached to the plate 15, 95 in parallel relation to the member 17. A vertical bore 26, is formed in the part 25, preferably in communication with a lateral bore 27, in the upper part of said member extending above said plate, which bore 100 is in communication with the atmosphere. The lower part of the bore 26 is in communication with a horizontal bore 28, which terminates in a valve-seat adapted to fit the conical portion 29, upon the opposite 105 end, of the double ended valve 24. The bores 26, 27 and 28, constitute an equalizing passage between the vacuum tank and the atmosphere. Said valve is provided with longitudinal stems 30 and 31, which 110 are coincident with its axis and are adapted to slide loosely in the bores 20 and 28. The

valve 24, is provided with a circumferential groove or notch midway between its ends, thereby forming a reduced portion 32, adapted to fit loosely in a notch 33, formed in a horizontal lever 34, one end of which lever is fulcrumed upon a stud 35, Figs. 3 and 4, rigidly attached to the under side of the plate 15.

A horizontal bar 36, Figs. 1 and 4, is rigidly attached to the lower portions of the members 17 and 25, between the ends of which bar is pivotally supported by means of a screw 37, a cam-member 38, having beveled cam-faces 39 and 40 respectively. Said cam-member is formed from sheet metal and is provided with a laterally extended arm 41, best shown in Fig. 1, to which is attached a float 42, of cork or other suitable material. A depending arm 43, Figs. 1 and 4, integral 15 with said cam member, has a horizontal portion 44, extending outwardly from its lower end, to which is attached the lower end of a coiled spring 45, the upper end of said spring being attached to the free end 20 of the lever 34. The lever is adapted to rest upon the upper peripheral surface of the cam 38 in position to be brought into contact alternately with the oppositely inclined cam surfaces 39 and 40 thereof as 25 hereinafter described.

The auxiliary tank 1 is maintained under normal atmospheric pressure by means of a tube 46, Fig. 1, having a vent passage 47, therein in communication with the atmosphere.

The operation of the device is as follows: As a result of the suction stroke in the engine cylinder, a vacuum is created through the tube 18 and vacuum passage 19, 35 and, assuming the valve 24 to be moved to the left-hand position, the passage 19, would be in open communication with the vacuum chamber, while the equalizing passage 28 would be closed. A partial vacuum would 40 thus be formed in the vacuum-chamber which would result in the closure of the check-valve 9.

Assuming the level of the liquid fuel in the vacuum-chamber to be below the float 50 42, the latter would appear in a reverse position from that shown, thereby maintaining the controlling valve in the position described. The suction caused by each piston stroke would serve therefore to draw liquid 55 fuel from the supply-tank 7 upwardly through the tube 6 and nipple 5 into the vacuum chamber. Upon the accumulation of a sufficient quantity to lift the float to the substantial position shown, or until the 60 peak or high point of the cam 38 shall have passed beneath the lever 34, the tension of the spring 45 acting upon the lever 34 which is free to be moved downwardly and laterally, causes an instantaneous movement of 65 the latter, thereby shifting the valve 24

longitudinally so as to effectually close the vacuum passage 19 and open the vent passage 28, thereby producing an equilibrium of pressure in the vacuum tank and permitting a discharge of the liquid therefrom to the auxiliary tank, to be delivered in turn to the carbureter. Whenever the float shall have descended sufficiently to cause the peak of the cam 38 to pass beneath the lever arm 34, the tension of the spring will 70 serve to shift the lever by causing it to slide downwardly and laterally upon the incline of the cam surface 39, thereby closing the vent or equalizing passage 26 and opening the vacuum passage 19. It will thus be seen 75 that a continuous supply of fuel will always be maintained in direct operative communication with the carbureter to meet varying conditions of load.

The fact that I am enabled to control the 80 simultaneous opening and closing of the vacuum and pressure equalizing passages from the vacuum-chamber by means of a single valve is of importance, in that it results in simplicity and certainty of action, 85 while eliminating the necessity of fine adjustments; it being understood that the valve actuating lever is always free to move the valve in either direction to its maximum limit.

Having thus described my invention, I claim:

1. A vacuum feed mechanism for internal combustion engines, comprising, in combination a vacuum tank, an engine, a fuel supply 100 tank, said engine and fuel supply tank being below the level of said vacuum tank, an auxiliary container, disposed to receive liquid by gravity from said vacuum tank, vacuum controlled means for opening and closing a 105 passage between them, a carbureter in communication with the intake manifold of the engine, a conduit for delivering fuel from said container to said carbureter, a vacuum passage leading from said vacuum tank to 110 the intake manifold of said engine, an equalizing passage leading from said tank to the atmosphere, said passage having oppositely disposed valve-seats, a duplex valve adapted to close one and open the other of said passages, a lever for actuating said valve, an oscillatory reversing cam for shifting the position of said lever, and a float in said vacuum chamber for actuating said reversing cam.

2. A feed controlling mechanism of the class described, comprising a vacuum tank, an engine, a fuel-supply tank, said engine and supply tank being below the level of said vacuum tank, an auxiliary container 125 below said vacuum tank to receive liquid fuel therefrom, vacuum controlled means for opening and closing an opening between them, a carbureter in open communication with the intake manifold of the engine, a 130

conduit for delivering fuel by gravity from said container to said carbureter, a vacuum passage leading from said vacuum tank to said intake manifold, a pressure equalizing passage leading from said tank to the atmosphere, said passages having oppositely disposed valve-seats, a reciprocating valve adapted to close one while opening the other of said passages, a pivoted reversing cam, a float in said vacuum chamber for actuating the same, a lever for actuating said valve, and a spring for yieldingly holding the same against said reversing cam.

3. A device of the class described, in which is combined, a vacuum tank, an engine, a fuel supply tank, said engine and supply tank being below the level of said vacuum tank, an auxiliary container below said vacuum tank to receive liquid fuel therefrom, said container being in communication with the atmosphere, vacuum controlled means for opening and closing communication between said vacuum tank and container, a carbureter in operative communication with the intake manifold of the engine, a conduit for delivering fuel from said container thereto, a vacuum passage leading from said vacuum tank to said intake manifold, an equalizing passage leading from said tank to the atmosphere, oppositely disposed valve seats at the beginning of said passages, a valve having cones upon the opposite ends and stems extending therefrom to slidably enter said passages, a laterally movable lever in operative connection with said valve, an oscillatory cam having downwardly and laterally inclined faces to alternately contact with said lever, a coiled spring for connecting the free end of said lever to a stationary point to cause said lever to slide downwardly and laterally upon one or the other of said inclined cam faces as the cam is oscillated in one or another direction, and a float in said tank in operative connection with said cam for shifting the same.

4. A feed device of the class described, in which is combined a vacuum tank, an engine, a fuel supply tank, said engine and supply tank being below the level of said vacuum tank, a chamber below said vacuum tank to receive liquid fuel therefrom, the same being in communication with the atmosphere, a check-valve interposed between the two, a carbureter in communication with the en-

gine intake, means for delivering fuel from said chamber thereto, a vacuum passage interposed between said vacuum tank and said engine intake, an equalizing passage leading from said tank to the atmosphere, oppositely disposed valve-seats in said tank at the entrance to said passages respectively, an interposed valve between said seats to alternately close one and open the other of said passages, an oscillatory cam, a movable member in operative connection with said valve and cam respectively to move said valve longitudinally when the cam is reversed, a spring for holding said movable member in yielding contact with said cam, and a float in operative connection with said cam for reversing the same.

5. In a device of the class described, the combination with an intake manifold of an engine and a main liquid fuel supply tank, of a vacuum tank at a higher level than that of said supply tank and in operative communication therewith, an auxiliary container open to the atmosphere and adapted to receive its supply from said vacuum tank, a carbureter in communication with said intake manifold, a check-valve interposed between said vacuum tank and said auxiliary container, means for delivering fuel from said auxiliary container to said carbureter, a vacuum passage leading from said vacuum tank to said manifold, an equalizing passage leading therefrom to the atmosphere, a double-ended cone-valve arranged to move longitudinally to simultaneously open and close one or the other of said passages, means in direct connection with said valve for moving it longitudinally, a reversing cam having oppositely inclined faces for alternately engaging said valve-moving means, a spring for pressing said valve-moving means against said cam, and a float in operative connection with said cam to alternately present one or the other of said inclined faces to said valve moving means as the float rises and falls.

In testimony whereof, I have signed this specification in the presence of two subscribing witnesses, this 29th day of January 1919.

FLOYD GARWICK.
